GEORGE B. SINCLAIR, OF GEORGETOWN, MAINE.

STARTER FOR ENGINES.

1,137,358.

specification of Letters Patent. Patented Apr. 27, 1915.

Application filed July 1, 1912. Serial No. 706,911.

To all whom it may concern:

Be it known that I, GEORGE B. SINCLAIR, a citizen of the United States and a resident of Georgetown, in the county of Sagadahoc, 5 and State of Maine, have invented certain new and useful Improvements in Starters for Engines, of which the following is a specification.

The object of this invention is the construction of improved means for starting internal combustion engines, and, while specifically designed for automobile engines, it is equally applicable to power boats, stationary engines using either gas or gasoline, 15 and other prime movers.

My invention consists essentially in providing means whereby a spring wound by the engine while in motion can be utilized for starting the engine whenever desired.

While this appears to be very simple, it is quite a difficult thing to work out practically, since the spring must not be wound up beyond a safe limit, but must instantly be released from the engine the instant such limit 25 is reached; after such winding, the spring must be held there; and must be capable of instant coupling to the engine when the latter is to be started, and of rotating the latter in the proper direction for a few turns 30 and then being automatically released therefrom.

Referring to the drawings forming part of this specification, Figure 1 is a side view, partially in section, of an engine starter embodying my invention. Fig. 2 is a face view of the spring drum. Fig. 3 is a sectional detail view of one of the clutch members. Fig. 4 is a view of a portion of a co-operating member of said clutch member. Fig. 5 is 40 a detail view of the automatic circuit closing device and operative parts. Fig. 6 is a perspective view illustrating certain details in connection with the electrically controlled connecting devices. Fig. 7 is a sectional view of a part of the same. Fig. 8 is a view of one of the clutch members. Fig. 9 is a central longitudinal sectional view through a portion of the elements illustrated in Fig. 1.

In Fig. 1, the reference numeral 1 designates the shaft of the internal combustion engine which is to be started; 2 is the fly-wheel thereof, and 3 the drum containing the spring 4 whose potential power is to be 55 utilized. Said drum is loose on the shaft

and also loose on the clutch sleeve 5, which sleeve 5 is slidably journaled upon the shaft 1 and the spring has one end fastened to the drum and the other end to the sleeve, as shown in Fig. 2.

In general, the operation of the starter is as follows: Power for winding said spring is communicated from said fly-wheel through a finger 6 fixed thereto to a longitudinally movable spur 7 carried by the wheel 9, journaled upon the shaft 1 and from said wheel through a finger 10 rigid therewith to a finger 11 rigid with said drum, said clutch sleeve being at the time disengaged from a clutch connection with said wheel, and in 70 clutch engagement with a fixed clutch member 12 so that said sleeve will not turn. Consequently, after a limited number of revolutions of the shaft, the spring will be 75 sufficiently wound.

By means hereinafter set forth, the instant the proper number of revolutions has been imparted to the drum 3 and the spring suitably wound, said movable spur 7 is withdrawn from its engagement with the finger 6 so that the shaft continues its motion without affecting said spring any further. The spring tends, of course, to unwind to its normal position, but by forming a section of the rim of the wheel 9 with teeth 13 and providing a detent 14 pivoted to any suitable support, said wheel cannot turn backward but holds the spring in its wound condition.

Now whenever the engine stops and it is 90 to be started, the clutch sleeve 5 is released from the fixed clutch member 12 and engaged with the clutch member 15 which is keyed on said shaft 1, as at 74 but turns freely within the wheel 9, said wheel being 95 journaled upon the shaft 1 between said clutch member 15 and a collar 75 fixed to the shaft 1 between the wheel 9 and the fly wheel.

A packing collar 73 is secured to the shaft 100 within the clutch member 15. The spring being now no longer held by said fixed clutch member, but being still held at one extremity by said detent and connecting parts, immediately rotates said shaft and 105 operates the engine until the latter is caused to start its proper propelling explosions.

I will now take up the detailed construction of said movable spur 7 and its operative elements: Referring to Fig. 6, it will be 110

seen that said spur is formed with an arm 16 pivoted on the spindle 17 supported by the wheel 9, a spring 19 normally holding the spur in its illustrated position. The 5 spur is held against the pressure of the finger 6 already referred to, by the engagement of its inner end 20 with the shoulder 21 of the latch 22 which is supported on a spindle 23 and normally retained in its illustrated 10 position by a light spring 24. Inasmuch as the strong pressure of the spur against the shoulder 20 will release it therefrom if the latch is not confined in its illustrated position, a lock 25 is provided which is pivoted 15 at 26 and yieldingly held in its illustrated position by a spring 27. The shoulder 29 of said lock supports the pressure of the latch and the action of said spur.

A pivotally supported armature 30 having a finger 31 engaging said lock and controlled by an electromagnet 32, serves to release the latch from the lock the instant the magnet is energized. As the latch flies back under the pressure of the spur 7 thus released, its finger 33 is caught behind the finger 31 of the armature and retained in such position against the urging of its spring 24, since the energizing of said magnet is arranged to be but momentary and the 20 spring 27 has returned the lock 25 and armature 30 to their illustrated positions in time to catch the latch before its return. The spring 34 is a very slender one and designed simply to keep the armature in contact with the lock 25. For energizing said electromagnet 32, the following arrangement is devised: The parts being as illustrated in Fig. 6, with the exception of the clutch operating lever 28, and the spur 7 being supported to cause the rotation of the wheel 9 and hence of the drum 3, the spring within the latter will be wound through the energy of the engine. It is necessary, however, to disengage said spur the moment 25 the spring has received its proper number of winds. To this end, the energization of the electromagnet 32 is effected through means controlled by a specified number of turns of the wheel 9. To do this, said wheel 30 is provided with a single tooth 35 (Fig. 5) followed and preceded by a slight recess, but the remainder of the periphery is smooth and contacting with two teeth of the spur gear 36. So long as this contact is 35 maintained, said gear cannot turn, but upon the passage of said tooth the gear will receive a limited segmental movement.

Rigid with said gear is a circular insulating surface exposing a single contact point 40 37, a stationary brush 39 being adapted to complete a circuit with said electromagnet whenever said brush and point meet. Hence the instant the wheel 9 has communicated the specified number of segmental movements to said gear to present said point 37

to said brush and thereby complete the circuit of said electromagnet, the spur 7 is released and further winding ceases.

The circuit is as follows: From a suitable current-source 40, the current traverses a 70 wire 41, framework 41' and the axle of gear 36, gear 36 and said point 37, brush 39, wire 42, brush 43, insulated contact ring 44, wire 45, electromagnet 32, wire 46, brush 47, bridging contact 49 carried by the latch 22, 75 brush 50, wire 51, insulated contact ring 52, brush 53, wire 54, brush 55, contact 56 (Fig. 1), wire 57, switch 58 and a short connection back to said source 40. The instant said electromagnet is thus energized, the latch 80 22 is released, and as it flies back under the impulse of the spur 7, the bridging contact 49 leaves the brushes 47, 50, and thus demagnetizes said electromagnet, permitting the lock 25 to engage and hold the latch in 85 its new position. These parts remain in such condition, with the spring fully wound, as long as desired, with the exception that, to save current, the switch 58 is opened. When the engine is at rest and it is desired to start 90 it, all that needs to be done is to throw the clutch lever 28 over to the position illustrated in Fig. 6, and thereby to disengage the clutch sleeve 5 from the stationary clutch member 12 and to engage it with the 95 clutch member 15, which, it will be remembered, is keyed on the shaft 1 but independent of the wheel 9. The latter being held from turning backward by the pawl or detent 14, similarly holds the drum 3 and so 100 causes the energy of the spring to be communicated to the clutch member 15 and shaft 1, and the engine to be rotated until well started. Ordinary clutches cannot be used here, for then the instant the clutch 105 sleeve was disengaged from the stationary clutch member and before it could be engaged with the clutch member 15, it would instantly unwind and produce no useful work. To obviate this, one of the clutches of 110 the clutch sleeve is provided with pivoted ribs 60 resiliently pressed outward, as shown in Fig. 3. Hence before the clutch members at one end of the sleeve have parted company, the resiliently held clutch ribs will 115 have engaged the associated clutch member, and by their yielding permit the clutch sleeve to move still farther along until the other clutch members have been wholly disconnected. After the engine is thus started, 120 the clutch lever is returned to its position shown in Fig. 1; the switch 58 is closed and the latch released from its last-described position. To enable this closing of the switch to thus affect said latch, another circuit is provided, which, while the same as that previously described from the source to the electromagnet 32, has for its return a part of the wire 46, wire 61, insulated contact ring 62, brush 63, wire 64, 125 wire 65, 130

contact 65, brushes 66 and 55, contact 67 and wire 57 back to the source. The latch 22 being now in its position illustrated in Fig. 6, with the spur 7 having been returned by its spring 19 into engagement with the shoulder 21 of said latch, the finger 6 of the fly-wheel comes into contact with said spur and proceeds to wind up the spring 4 in the manner already described.

10 The contact rings 44, 52, and 62 are fixedly mounted upon the periphery of the hub X projecting centrally from the wheel 9, while the clutch member 15 is free within said hub. This allows the ring to rotate 15 with the wheel 9 and allows for the permanent wiring 45, 51, and 61.

It should be noted that the clutch member 15 does not have square sided ribs 70 like the ribs 71 of the clutch member 12 20 (Fig. 8), but the former are what may be termed ratchet ribs, as shown in Fig. 4, so that after the engine has started and before the clutch sleeve can be thrown out of engagement with said clutch member 15, said 25 ratchet ribs will slide over the yielding ribs 60 and so not rotate the sleeve and spring with the engine.

Although I have above described the clutch sleeve 5 as provided with resiliently 30 pressed ribs 60 at one end alone, I prefer to have such ribs at both ends of the sleeve, in order to insure that when the sleeve is thrown over toward the fixed clutch 12 there 35 may be no danger of the sleeve's clutch failing to enter the clutch member 12, as might be the case were the ribs non-resilient and should such ribs of one member longitudinally impinge against the ends of the ribs of the other member.

40 What I claim as my invention and for which I desire Letters Patent is as follows, to wit:—

1. A starting device for engines comprising a shaft rotatably connected with an engine, a drum loosely mounted on said shaft, means for communicating rotary motion from said shaft to said drum, means for disconnecting the same, a clutch sleeve loosely mounted on said shaft, means for longitudinally moving said sleeve on said shaft, a spring terminally attached to said sleeve and drum, clutch members at the ends of said sleeve, a stationary clutch member adapted to be engaged by one of the clutch 45 members of said sleeve, and a clutch member fixed on said shaft and adapted to be engaged by a clutch member of said sleeve, said clutch members being adapted to permit the clutch sleeve to engage with the clutch 50 member fixed to the shaft while still in engagement with the stationary clutch member.

2. The combination with an engine, of a shaft connected therewith, a clutch sleeve loosely mounted on said shaft, means for longitudinally shifting said sleeve, a drum

rotatably mounted on said sleeve, a coiled spring terminally attached to said sleeve and drum, a stationary clutch member adapted to be engaged by said clutch sleeve, a clutch member fixed on said shaft and adapted to 70 be engaged by said sleeve, a wheel loosely mounted on said shaft, movable means for communicating the rotation of said shaft to said wheel, means for preventing said wheel from turning backward, and means for communicating motion from said wheel to said drum.

3. An engine starter comprising a shaft, a clutch sleeve loosely mounted thereon, a stationary clutch member adapted to be engaged by one end of said sleeve, a spring terminally attached to said sleeve, means for winding said spring and holding it in a wound condition, a clutch member fixed on said shaft, and means for slidably shifting 80 said sleeve, one end of said sleeve being provided with pivoted resiliently supported ribs, and the clutch member co-operating therewith being formed with ratchet ribs, whereby said clutch sleeve can be made to engage 85 one clutch member before being entirely disconnected from the other.

4. A starter for engines comprising a shaft, a fly-wheel fixed thereon, a wheel loose on said shaft and having a movable spur, a finger rigid with said fly-wheel and adapted to engage said spur, a spring adapted to be wound by said wheel's rotation, means for retaining said spring in a wound condition, means for transmitting motion from said 95 wheel to said shaft, and means for releasing said spur after a predetermined number of turns of said wheel.

5. A starter for engines comprising a shaft, a wheel loose on said shaft and having a movable spur, means for transmitting motion from said wheel to said shaft, means rigid with said shaft for engaging said spur and turning said wheel, a spring wound by said wheel, means for holding said spring 100 in its wound condition, a latch normally locking said spur in its engaging position, an electromagnet, means actuated by the energizing of said electromagnet to release said latch, and means for delivering energizing current to said electromagnet after a predetermined number of turns of said wheel.

6. A starter for engines comprising a shaft, a wheel loose on said shaft and having a movable spur, means for transmitting motion from said wheel to said shaft, means rigid with said shaft for engaging said spur and turning said wheel, a spring wound by said wheel, means for holding said spring 110 in its wound condition, a latch normally locking said spur in its engaging position, an electromagnet, means actuated by the energizing of said electromagnet to release said spur from said latch, a source of cur- 115 120 125 130

rent, a rotatable member adapted to be rotated once by several rotations of said wheel, a contact carried by said member, a stationary brush reached by said contact at 5 each rotation of said member, and a circuit embracing said electromagnet, source, contact and brush.

7. A starter for engines comprising a shaft, a wheel loose on said shaft and having 10 a movable spur, means for transmitting motion from said wheel to said shaft, means rigid with said shaft for engaging said spur and turning said wheel, a spring wound by said wheel, means for holding said spring 15 in its wound condition, a latch normally locking said spur in its engaging position, an armature, a lock for said latch controlled by said armature, an electromagnet controlling said armature, and means for energizing said electromagnet.

8. A starter for engines comprising a shaft, a wheel loose on said shaft and having a movable spur, means for transmitting motion from said wheel to said shaft, means 20 rigid with said shaft for engaging said spur and turning said wheel, a latch for said spur, an electromagnet controlling said latch, means for automatically energizing said electromagnet after a predetermined 25 number of revolutions of said wheel, and immediately thereafter demagnetizing it, a 30 spring, means for winding said spring actuated by the predetermined rotations of said wheel, and means for holding said spring in 35 its wound condition.

9. A starter for engines comprising a shaft, a wheel loose on said shaft and having a movable spur, means rigid with said shaft for engaging said spur and turning 40 said wheel, an electromagnet controlling said spur, a clutch sleeve loose on said shaft, a stationary clutch member adapted to be engaged by one end of said sleeve, a clutch member adapted to be engaged by the other 45 end of said sleeve, a drum loosely mounted on said sleeve, a spiral spring terminally attached to said sleeve and drum, a movable member for shifting said sleeve into clutch engagement with either of said clutch members, insulated contacts carried by said 50 sleeve-shifting member, stationary brushes coöperating with said contacts, a switch, a source of current wired to said switch, con-

nctions between two of said contacts and said switch, connections between said brushes and electromagnet, connections between the other of said contacts and said electromagnet, a stationary brush wired to said electromagnet, a contact in circuit with said current-source and means for closing the 60 circuit through the last-named contact and the last-named brush after a predetermined number of revolutions of said wheel.

10. A starter for engines comprising a shaft, a wheel loose on said shaft and having 65 a movable spur, means rigid with said shaft for engaging said spur and turning said wheel, a latch having a shoulder engaged by said spur, a lock for said latch, an armature controlling said lock, springs for returning said latch, lock, armature and spur to their normal positions, an electromagnet controlling said armature, a bridging contact carried by said latch, insulated brushes in touch with said contact when said latch 70 is in its normal position, a source of current, connections between said source and electromagnet, means for opening and closing the circuit between said source and electromagnet after a predetermined number of revolutions 75 of said wheel, connections between the other pole of said source and said electromagnet, connections between said electromagnet and one of said brushes, connections between the other of said brushes, and the 80 last-named pole of said source and means for switching either of the two last-named connections at will in and out of circuit.

11. An engine starter comprising a shaft, a clutch sleeve loosely mounted thereon, a stationary clutch member adapted to be engaged by one end of said sleeve, a spring terminally attached to said sleeve, means for winding said spring and holding it in a wound condition, a clutch member fixed on 90 said shaft, and means for slidably shifting said sleeve, the ends of said sleeve being provided with resiliently yielding clutch-ribs.

In testimony that I claim the foregoing 100 invention, I have hereunto set my hand this 28 day of June, 1912.
